HOSIERY AND METHOD OF MAKING THE SAME

Joseph L. Beers, Bloomfield, N. J., and Hans J. Straussberger, Brooklyn, N. Y., assignors to Julius Kayser & Co., Brooklyn, N. Y.

Application January 6, 1938, Serial No. 183,572

14 Claims. (Cl. 66—183)

The present invention generally relates to hosiery and method of making the same and, more particularly, to stockings of the type shown and described in co-pending application, Serial Number 150,674, filed June 28, 1937, in the name of Charles A. Kaufman, that is, stockings commonly known as mesh stockings and having a combined leg and instep fabric cut to shape from open work fabric, such as mesh, lace, or like material, and 10 a welt and foot of flat weft knitted fabric.

The invention has for one of its main objects the provision of a stocking of the type referred to, having an improved connection between the leg and instep portion and the welt and foot 15 sections.

Another important object of the invention resides in the provision of a stocking having a leg and instep of mesh fabric and a welt and foot of weft knit fabric, wherein is devised means to 20 effect a reinforced and finished connection between the fabrics capable of resisting strain and stresses to which the stocking is subjected when put to ordinary use, while adapted to impart a smooth finished appearance at the points of the fabric interconnection.

Still another important feature of the invention resides in the provision of a stocking consisting of a mesh fabric leg and instep part and flat knitted welt and foot parts, said parts being so 25 constructed that they may be easily and conveniently handled to effect their interconnection, thereby facilitating the manufacture of the stocking and making it possible to produce the same on a practical commercial basis.

The invention further contemplates the provision of a method of knitting the welt and foot fabrics and connecting them to a cut leg and instep fabric in such a way that a plurality of fabric thicknesses are formed, between which is inserted and imprisoned a substantial amount of the leg fabric, thereby resulting in producing a 30 seam having an increased strength and a pleasing finished appearance.

Other important objects and advantages of the 35 invention will be in part obvious and in part pointed out hereinafter.

In order that the invention and its mode of operation may be readily understood by persons skilled in the art, we have, in the accompanying drawings and in the detailed description based thereupon, set out possible embodiments of the invention.

In these drawings:

Figure 1 is an elevation illustrating a finished 40 stocking constructed in accordance with the invention.

Figure 2 is a composite view illustrating the 45 cut leg and instep blank, and the welt and foot construction.

Figures 3 to 5 inclusive are diagrammatic rep-

resentations of the successive steps followed in uniting the welt to the corresponding portion of the leg fabric in accordance with one mode of practicing the invention.

Figure 6 is a section taken on line 6—6 of 5 Figure 5.

Figures 7 to 11 inclusive are diagrammatic representations of the various steps followed in knitting the foot fabric.

Figure 12 is a detail in perspective illustrating 10 one mode of connecting the leg fabric blank with a part of the foot fabric.

Figure 13 is a section taken on line 13—13 of Figure 12.

Figures 14 to 19 inclusive are diagrammatic 15 representations of the steps followed in knitting the welt and uniting it to the leg blank in accordance with a modification of the invention.

Having more particular reference to the drawings, wherein like characters of reference will designate corresponding parts throughout, we have shown in Figure 1 a complete and finished stocking 1 consisting of a leg 2, including an instep 3, a foot 4, and a welt 5.

The leg 2 is preferably formed with a leg fabric 25 blank 6 cut, substantially in the shape represented in Figure 2, from a sheet of suitable fabric, preferably mesh, lace, or open work warp knit fabric. It will be noted that the opposite side edges 7 of the blank 6 from the marginal edge 8 along 30 the line a—a at one end of said blank are cut and fashioned so that the blank will suitably fit the shape of a human leg when said edges 7 are sewed together to form the stocking.

It will also be noted that the edges 9 along the 35 line b—b at the lower portion of the blank 6, are cut at substantially right angles with respect to the edges 7 and to the edges 10, the latter extending between the points defined by said line b—b and line c—c which is along the marginal 40 edge 11 at the other end of the blank.

Attention is called to the fact that the opposite portions of the leg fabric blank adjacent the marginal edges 9 and 10 are longitudinally slit, as shown at 12, whereby to provide a pair of 45 depending tabs 13 for the purpose to be later specified.

It is, of course, to be understood that the cutting of the blank along the edges 9, as shown herein, is specifically intended for the formation 50 of an ordinary high-splice heel, but if it is desirable to form a different type of heel, such as a pointed heel, then the blank may be cut so that the edges 9 will be at an angle different from that shown, in order to adapt itself to the formation 55 of the desired type of heel.

The section of the blank from the line b—b to the line c—c, (the length of which section may vary, depending upon the foot size), constitutes the instep 3, and those portions thereof adjacent

the edges 9, 10, and 11 are adapted to be connected to our improved foot 4, the construction of which is more clearly shown in Figure 2.

As represented in said Figure 2, the foot 4 is made from a full-fashioned fabric blank 14 comprising a pair of complementary heel fabrics 15, a pair of complementary sole fabrics 16, and a toe fabric 17.

One end of each heel fabric 15 is provided with 16 a double-ply welt-like fabric projection 18 extending from the heel fabric demarking line 19. The other end of each heel fabric 15 is provided with a topping course 20 and a topping tab 22. It will, of course, be understood that each heel 15 fabric may be narrowed, as shown at 23, to impart a proper curve shaping to one selvedge edge 24 thereof, the other selvedge edge 25 being substantially straight. In this connection, it is to be noted that the selvedge edges 26 and 27 of the 20 welt-like fabric projection 18 extend as a continuation of the selvedge edges 24 and 25 of the heel fabrics. Whereas the two heel fabrics 15 are of identical construction, they are so manufactured that one serves as the right heel and 25 the other as the left heel.

The sole fabrics 16 start at the selvedge edges 25 of the heel fabrics 15, extend therefrom for a length sufficient to correspond to the desired size of the foot being knitted and terminate at the 30 point where the knitting of the toe begins.

Each sole fabric 16 may be narrowed in the usual way in the vicinity of its starting and terminating portions, as represented at 28 and 29, whereby the outer selvedge edges 30 may assume 35 the proper curve shape, the inner selvedge edge 31 remaining substantially straight.

The toe fabric 17 has its side portions 32 interknit with the sole fabrics 16 so that the selvedge edges 33 of said toe fabric become a continuation 40 of the outer selvedge edges 30 of the sole fabrics.

Interknit, as at 34, to the intermediate portion of the toe fabric, is a double-ply welt-like portion 35 extending between the sole fabrics 16 and having a width slightly greater than the distance 45 from the inner selvedge of one of said sole fabrics to the inner selvedge of the remaining sole fabric so that the selvedge edges 36 of said welt-like portion 35 overlap the selvedge edges 31 of said sole fabrics.

The usual gores 38, topping course 39, and topping tab 40, may be provided in the toe fabric 17.

The welt 5 may be of any suitable or desirable construction but, as represented in the drawings, is preferably made from a flat knitted fabric blank 41 of general rectangular formation with 55 the selvedge edges 42 thereof adapted to become substantially aligned with the selvedge edges of the adjacent portion of the leg fabric blank 6 when connected thereto. The welt fabric blank 41 also is preferably provided with a medial picot course 43 along which said blank may be folded, whereby to form the commonly known double welt.

In knitting the foot blank, the heel fabrics 15 are first made on any type of flat knitting machine capable of adapting itself to the work, for 65 instance, on the well-known "Reading" full-fashioned knitting machine with which those skilled in the art are familiar.

The mode of procedure in knitting the heel fabrics will be clearly understood by the showing 70 made in Figures 7 and 8 inclusive.

When starting the heel fabrics, an ordinary welt bar W is brought into operative relation with the needles N, sinkers S, and knockover bits K to

engage, in the usual way, the initial knitted courses and subsequently draw the fabric out of the knitting field as the knitting of said fabric progresses.

A sufficient number of courses are knitted to 5 form the welt-like fabric projection 18 which is folded over, welt fashion, as indicated by the arrow A in Figure 7, to provide a double thickness of fabric. It will be noted that during the knitting of said projection, the fabric is slightly narrowed, then widened, as shown at 44 and 45 respectively, and a pair of picot courses 46 are knitted in spaced relation so that, upon folding the fabric to form the double thickness, the narrowed and widened portions 44 and 45 and the picot 15 courses 46 will lay in diametrically opposed relationship.

With completion of the welt-like fabric projection 18, the knitting is continued to finish the heel fabric 15 which is narrowed, as at 23, to 10 impart shaping thereto and terminates with the ordinary topping course 20 and topping tab 22. As hereinbefore stated, the heel fabrics 15 are so knitted that one forms the right heel while the other forms the left heel.

It will be appreciated that the heel fabrics of the character described may be manufactured in stock quantities and at odd times, inasmuch as the heel fabrics need not be utilized immediately but may be stored for future use when foot blanks 30 are required.

When making the foot blank 14, two completed heel fabrics 15, that is, one right and one left heel fabric, are transferred on a knitting section of a commonly known full-fashioned footer knitting machine by engaging the loops at the selvedge edge 25 of said heel fabrics with a certain number of end needles, the heel fabrics being relatively disposed so that the welt-like projections 18 will be facing each other in a manner more fully represented in Figure 9. The two heel fabrics 15 are so placed on the needles of the footer knitting machine that the distance therebetween will correspond to the width of the instep.

With the heel fabrics thus transferred on the knitting machine, the latter is operated to simultaneously knit the pair of sole fabrics 16, one sole fabric being knitted onto each heel fabric. In knitting the sole fabrics, we prefer to use one yarn carrier to form each sole fabric, each carrier being separately operated, that is, each carrier being individually connected to a separate carrier bar operable through the usual well-known yarn feeding mechanism of an ordinary full-fashioned footer to impart an independent reciprocatory movement to the respective carriers for causing the same to lay their yarn over the required number of needles.

Of course, it is to be understood that additional carriers may be brought in, to work in conjunction with each of the main carriers, for instance, when it is desirable to lay a reinforcing thread or to knit a plated fabric and, in that event, the additional carriers are adjusted to operate in proper relation with respect to the main carriers, a matter well understood by those skilled in the art.

During the knitting of the sole fabrics 16, the usual narrowing mechanism is caused to function, as is well known in the art, to form the 70 narrowing 28 and 29 for the purpose hereinbefore specified.

When there has been knitted a sufficient amount of courses to constitute the sole fabrics, that is, when the knitting has been carried out 75

to the point where the knitting of the toe is to begin, the machine is stopped and a small ready-made welt portion 35 is transferred in any suitable manner along the marginal course 46 on the 5 intermediate needles N1 so as to span the spacing between the sole fabrics.

The small welt portion 35 is preferably provided with intermediate picot courses 46' similar to those provided in the welt-like projections of 10 the heel fabrics 15. The various fabrics being thus arranged, the knitting is carried out so that the yarn is fed in one continuous stroke over the end and intermediate needles to knit the toe fabric 17 which thus becomes interknitted with 15 said sole fabrics 16 and small welt portion 35 as indicated at 34.

In knitting the toe fabric, the narrowing mechanism of the knitting machine is operated to form the toe gores 38; the knitting machine is 20 further operated to knit as usual the topping course 39 and topping tab 40 onto the toe fabric 17.

Attention is called to the fact that the narrowing marks 29 at the terminating portion of the 25 sole fabrics 16 are preferably located to converge towards the connecting point between said sole fabrics and the small welt portion 35. In this manner, there is formed a simulated diamond point resembling the diamond point in the toe, 30 which imparts a pleasing symmetrical appearance as illustrated in Figures 1, 2, and 11.

The completed foot blank is then ready to be connected to the leg blank and the steps which we prefer to follow in effecting this 35 connection will now be described:

The welt-like projections 18 of the heel fabrics 15 and the small welt portion 35 of the toe fabric 17 are folded along their respective picot courses 46 and 46' in the manner more clearly 40 shown in Figures 12 and 13, thus forming a re-entrant portion 50 between the walls of which is inserted the corresponding portions of the leg fabric blank, that is, the depending tabs 13 and the lower marginal portion of the instep adjacent the edge 11.

The layers of fabrics are then sewed through and through, preferably by means of a triple needle stitching machine, thus forming a rigid seam between the leg and foot at the heel and toe parts, 50 said seams consisting of three lines of stitchings, as represented at 51. Because of the provision of the picot courses 46 and 46', it will be appreciated that finished edges 52 appear at the seam which, in connection with the lines of 55 stitchings 51, enhance the general appearance of the stocking.

Moreover, the provision of the picot courses facilitates the folding of the welt-like fabric projections and the small welt portion because the 60 picot courses tend to crimp the fabric along a straight line.

The seaming of the heel and toe fabrics, of course, leaves free the marginal side edges 10 of the instep 3, which edges may then be sewed 65 or seamed, according to the usual mode of procedure, to the corresponding selvedge edges 27 of the heel welt-like projections 18 and to the selvedge edges 31 of the sole fabrics to form the seam 53 (Fig. 1), said seam 53 continuing along the selvedge edges 36 of the toe welt-like portion 35, thereby joining the latter to the sole fabrics and thus completing the connection of the foot 70 blank to the leg blank.

Although the welt blank 41 may be connected to the corresponding portion of the leg blank in

any suitable manner, we prefer to effect the connection as follows:

The welt blank is laid flat with the right side of the fabric facing up. The upper marginal portion of the leg blank is then placed upon the 5 welt blank so that the edge 8 of said leg blank is substantially aligned with one of the corresponding edges of the welt blank. The welt blank is then folded along the picot course 43 and the other marginal edge thereof brought over the 10 corresponding edge of the leg fabric blank 6. The superimposed edges of the welt blank, with the leg fabric therebetween, are then sewed together, preferably by means of a triple needle stitching machine, as indicated at 54. 15

The welt is then turned inside out, which forms a hem 55 at the point of connection between the welt and leg fabrics, enclosing the seam and exposing the right side of the welt fabric.

The stocking is completed in the usual manner, that is, the heel fabrics 15 are looped together by placing the topping course 20 in engagement with the points of a looping machine by means of the topping tabs 22 which are thereafter ravelled or cut off in the course of the operation. The toe fabric is looped along the topping course 39, the tab 40 having been ravelled or cut off after serving its purpose of topping on, and finally the connected leg, foot, and welt blanks are sewed along their respective edges 7, 24, 26, 30 30, 33, and 42 to form the back seam 56 (Fig. 1.)

It is to be understood that the foregoing description sets forth a possible embodiment of the invention and that the same is capable of modifications without departing from the essence of 35 the invention. For instance, instead of effecting a seaming connection between the welt and leg fabric blanks in the manner hereinbefore set forth, the connection may be had by means of interknitting and seaming operations, diagrammatically shown in Figures 14 to 19 inclusive. To accomplish this type of connection, a welt blank 41' is knitted upon any suitable well known knitting machine. Prior to the turning of the welt, the corresponding edge portion of the leg fabric blank 6' is topped on the knitting needles N2 so that a short section 6a of said leg fabric blank projects from the inner side of the needles, the remaining portion of the leg fabric blank being allowed to drop off one side of the welt blank, as 50 represented in Figure 14 of the drawings.

The welt blank is then turned, as is customary, and a course of knitted loops 41a is formed to interknit the walls of the welt blank with the corresponding portion of the leg fabric blank therebetween; the short section 6a of the leg fabric blank is subsequently brought over the needles to disengage the same and a few courses knitted to provide a welt extension 41b substantially equal in size to the short section 6a of leg fabric blank. 55 The welt blank is then removed off the machine and, as shown in Figure 18, the welt extension 41b and short section 6a of leg fabric blank sewed together, preferably by means of a triple needle stitching machine, as illustrated at 54'. The welt blank is finally turned inside out, as shown in Figure 19, forming a hem 55' enclosing the interknit and seamed connection, after which the stocking is completed, as hereinbefore described. 60

It is also to be understood that the welt may 70 be attached to the leg in the same manner as done at the heel and toe, by forming the welt with the necessary extension.

In concluding, we wish it to be understood that other modifications in the mode of practicing and

constructing the invention may be made and, therefore, any modifications coming within the scope of the subjoined claims are to be considered within the spirit of the invention.

5. What we claim is:

1. In a stocking having a cut fabric leg portion and a knitted stocking section, connecting means between parts of the leg portion and the stocking section consisting of a welt-like extension made with the stocking section and folded to form a re-entrant portion enclosing a corresponding part of the leg fabric, and stitchings passing through said welt-like extension and the part of the leg fabric therebetween for connecting the same.
10. 2. In a stocking having a cut fabric leg portion and a knitted stocking section, connecting means between parts of the leg portion and the stocking section consisting of a double ply welt-like extension, each ply having an intermediate picot course, said welt-like extension being folded along the picot course to form a re-entrant portion with outer picot edges enclosing a corresponding part of the leg fabric, and stitchings passing through said welt-like extension and the part of the leg fabric therebetween for connecting the same.
15. 3. In a stocking having a cut fabric leg portion and a knitted foot section, connecting means between the heel of said foot section and the corresponding part of said leg portion consisting of a welt-like extension made integrally with said heel and folded to form a reentrant portion enclosing a corresponding part of the leg fabric, and stitchings passing through said welt-like extension and the part of the leg fabric therebetween for connecting the same.
20. 4. In a stocking having a cut fabric leg portion and a knitted foot section, connecting means between the toe of said foot section and the corresponding part of said leg portion consisting of a welt-like extension made integrally with said toe and folded to form a re-entrant portion enclosing a corresponding part of the leg fabric, and stitchings passing through said welt-like extension and the part of the leg fabric therebetween for connecting the same.
25. 5. In a stocking having a cut fabric leg portion and a knitted foot section, connecting means between the heel and toe of said foot section and the corresponding part of said leg portion consisting of welt-like extensions made integrally with said toe and heel, each of said extensions being folded to form a re-entrant portion enclosing a corresponding part of the leg fabric, and stitchings passing through said welt-like extension and the part of the leg fabric therebetween for connecting the same.
30. 6. In a stocking having a leg portion cut to shape from open mesh fabric and a stocking section knitted to shape on a full-fashioned knitting machine, connecting means between parts of the leg portion and the stocking section consisting of a welt-like extension knitted integrally with the stocking section and folded to form a re-entrant portion enclosing a corresponding part of the leg fabric, and stitchings passing through said welt-like extension and the part of the leg fabric therebetween for connecting the same.
35. 7. In a stocking having a leg portion cut to shape from open mesh fabric and a foot section knitted to shape on a full-fashioned knitting machine, connecting means between parts of the leg portion and the foot section consisting of a welt-like extension knitted integrally with the

heel and toe of the foot section and folded to form a re-entrant portion enclosing a corresponding part of the leg fabric, and stitchings passing through said welt-like extension and the part of the leg fabric therebetween for connecting the same.

8. A stocking having a cut fabric leg portion and a shaped knitted fabric stocking section connected to the corresponding part of the leg fabric portion, said stocking having a part provided with a welt-like extension folded inwardly of itself to provide a re-entrant portion enclosing a corresponding part of the leg fabric, and stitchings passing through said welt-like extension and the part of the leg fabric therebetween for connecting the same.

9. A stocking having a cut open-work fabric leg portion and a full-fashioned knitted fabric foot portion connected to the corresponding part of the leg fabric portion, said foot portion having an interknitted welt-like extension folded inwardly of itself to provide a re-entrant portion enclosing a corresponding part of the leg fabric, and stitchings passing through said welt-like extension and the part of the leg fabric therebetween for connecting the same.

10. A stocking having a cut-open-work leg portion and a full-fashioned knitted foot portion connected at its inner marginal edges to the corresponding part of the leg portion, said foot portion consisting of a pair of sole fabrics knitted as a continuation of said heel fabrics, and a toe fabric knitted as a continuation of said sole fabrics, said heel and toe fabrics each having a welt-like extension folded to form a re-entrant portion enclosing a corresponding part of the leg fabric, and stitchings passing through said welt-like extension and the part of the leg fabric therebetween for connecting the same.

11. A full-fashioned foot fabric blank adapted to be connected to a cut leg fabric blank, said foot fabric comprising a pair of heel fabrics, each having a double ply welt-like extension projecting therefrom and folded to form a re-entrant portion to enclose between the folds thereof a corresponding part of said leg fabric blank for seamed connection therewith.

12. A stocking comprising a cut open-work leg fabric and a knitted double-ply welt fabric having a combined, interknit and sewed connection with said leg fabric, said connection being hidden between the plies of the welt.

13. The method of uniting a stocking leg fabric section to the fabric of another part of a stocking comprising knitting the stocking part fabric with a double ply welt-like projection, folding said double ply welt-like projection to form a re-entrant portion, inserting the corresponding portion of the stocking leg fabric, and stitching said folded welt-like extension with the portion of the leg fabric therebetween.

14. The method of uniting a stocking leg fabric section with the fabric of another part of a stocking comprising knitting the stocking part fabric with a double ply welt-like projection, forming a picot course in each ply, folding said double ply welt-like projection along the picot course to form a re-entrant portion with outer picot edges, inserting the corresponding portion of the leg section, and stitching said folded welt-like extension with the portion of the leg fabric therebetween.

JOSEPH L. BEERS.

HANS J. STRAUSSBERGER.
